MESNE ASSIGNMENTS, TO THE BETTENDORF COMPANY, OF BETTENDORF, IOWA, A
CORPORATION OF IOWA

CAR TRUCK

Original application filed April 9, 1928, Serial No. 268,511, now Patent No. 1,787,031, dated December 30, 1930. Divided and this application filed June 11, 1930. Serial No. 460,406.

This invention relates to railway car trucks and more particularly to the construction of the side frames and the mounting of the bolster, spring plank and bolster supporting springs in the side frames, the present application being a division of our co-pending application, Serial No. 268,511, filed April 9, 1928, which has since become Patent No. 1,787,031, issued December 30, 1930.

10 The invention has for an object to provide a side frame construction in which the spring seating portion of the tension chord is effectively reinforced to provide ample strength to enable the side frames to bear the load imposed thereon through the bolster springs without distortion and further to provide a side frame which is so constructed as to permit a compact nesting of the bolster supporting springs with the spring nest centered with respect to the side frames and with all of the springs supported on the tension chord at the same level.

A further object is to provide a truck in which the side frames are so constructed as to permit a compact nesting of the supporting springs whereby a greater number of springs may be employed in a truck of a given wheel base and in which the springs occupy a minimum space longitudinally of the frame and transversely thereof.

30 A further object is to provide a side frame in which a bolster opening is provided between upright columns connecting the compression and tension chords, in which the 35 portion of the tension chord between the columns is formed to provide a flat spring support extending from one column to the other so that the entire space between the columns may be utilized to receive a nest of bolster 40 supporting springs and in which the tension chord is effectually strengthened by diagonally disposed reinforcing webs at opposite sides of the flat spring supporting portion.

45 A further object is to provide a spring plank which is formed with flat widened end portions which serve as spring seats and which are formed to interlock with the side frames, the widened portions of the spring plank fitting in the recess between the re-
50 inforcing webs, the narrow body portion of

the spring plank providing space for the brake beams so that a relatively large number of springs may be employed in a truck having a relatively short wheel base.

A further object is to provide a side frame in which the full width of the bolster opening may be utilized for bolster supporting springs and in which guides are provided for the bolster which effectively hold the bolster against lateral, endwise and turning movements in the side frame. 66 60

A further object is to provide a truck having side frames with relatively wide bolster openings adapted to accommodate a relatively long nest of bolster supporting springs and to provide bolster guiding means which does not interfere with the proper positioning of the brake hanger brackets. 65

With the above and other objects in view, the invention may be said to comprise the truck as illustrated in the accompanying drawings hereinafter described and particularly set forth in the appended claims, together with such variations and modifications thereof as will be apparent to one skilled in the art to which the invention appertains.

Reference should be had to the accompanying drawings forming a part of the specification in which:

Figure 1 is a side elevation of a car truck embodying the invention.

Figure 2 is a section taken on the line indicated at 2-2 in Fig. 1.

Referring to the accompanying drawings, the truck is provided with side frames each of which may be in the form of a one piece casting, each having a compression chord 1 and a tension chord 2, the tension chord having a central horizontal spring supporting portion 3 and inclined end portions 4 which join the horizontal portion 3 to the ends of the compression chord 1. At each end of the horizontal portion 3, the tension chord is connected to the compression chord by an integral upright column 5, the columns 5 being spaced apart a sufficient distance to form a bolster receiving opening between them. The ends of a suitable bolster 6 extend into

the bolster receiving opening between the columns 5 and are of a width to fit between the flat inner faces of the inwardly projecting guide portions 8 of the columns 5.

5 The ends of the bolster 6 are provided with laterally projecting guide flanges 9 which provide channels to receive the projecting guide portions 8 of the columns which terminate a sufficient distance above the bottom 10 of the bolster receiving opening to provide an enlargement 10 in the lower portion of the bolster receiving opening of sufficient width and depth to permit the flanged end of the bolster to be inserted in the opening beneath 15 the guide portions 8 of the columns and to be lifted into interlocking engagement with the guide portions 8. The sides of the bolster have relatively wide flat faces adapted to bear against the flat faces 8 of the guide columns 20 so that in all positions of the bolster within the bolster receiving openings, the bolster is rigidly held against movements bodily in a lateral direction and against turning movements. In addition, the guide flanges 9 engaging opposite sides of the columns 5 positively hold the bolster against endwise movement.

The horizontal portion 3 of the tension chord has a flat web 11 extending across the 30 top thereof and projecting laterally beyond the opposite sides of the body portion of the chord forming horizontal side flanges 12 which provide a relatively wide spring support immediately beneath the end of the bolster. The flanges 12 are reinforced by vertical webs 13 which connect the under sides of the flanges with the body of the tension chord. The flat web 11 extends from the base of one column 5 to the base of the other 40 so that a relatively wide flat spring support is provided along the center line of the side frame.

The provision of a relatively long horizontal spring supporting portion in the tension chord tends to weaken the tension chord since the load imposed through the supporting springs tends to cause the tension member to assume the shape which would be assumed by a flexible tension member supported at the ends of the compression chord and subjected to a similar load. The tension chord has a weak point at the juncture of the horizontal portion with the columns 5 and inclined end portions 4 of the tension chord 50 and, in order to effectively strengthen these portions of the tension chord, reinforcing webs 14 extend across the lower corners of the bolster receiving opening, these webs merging into the flanges 12 at points spaced 60 inwardly from the columns 5 and extending upwardly from the flanges 12 and merging into the inner and side faces of the columns near the junction of the tension chord and the columns 5. The webs 14 are formed with 65 outer portions forming continuations of the

flanges 12 and with inner portions curved inwardly across the faces 8 of the columns 5 toward the center and forming a rounded recess 15 above the web 11 at the base of each of the columns.

70 It will be seen, therefore, that due to the provision of the web 14, a very long spring seat may be obtained substantially along the longitudinal center line of the side frame without sacrifice of strength.

75 A spring plank 16 of channel form connects the horizontal portions 3 of the opposite side frames and the bottom or web of the channel shaped spring plank which is preferably flat is widened at each end to provide rounded lateral projections 18 which are of a size and shape to substantially fit in the rounded recesses 15 at opposite sides of the bolster opening.

80 The lateral projections 18 of the spring plank are each of a size and shape to accommodate one of the bolster supporting springs 20 so that the end springs of the group or nest of springs may be positioned in close proximity to the columns 5 and supported at 90 the same level as the other springs of the group. The width of the bolster opening may be varied to provide a seat for as many springs as desirable for the particular truck for which the side frame is designed and the 95 springs may be arranged with a central row extending centrally of the side frame and with additional springs positioned on opposite sides of the central row and supported by the flanges 12 as shown in Fig. 3.

100 It will be obvious that various groupings of springs may be employed and that the present invention permits the use of a relatively large number of bolster supporting springs which are all of uniform length and through which the load is transmitted uniformly to the side frames.

105 It will further be evident that the bolster guiding means provided permits the bolster to have vertical movements, but rigidly holds 110 the bolster against endwise, lateral and turning movements and that the bolster is effectively guided by reason of its full engagement with the flat inner faces of the guide columns.

115 It will also be apparent that the present invention provides a side frame designed to support a relatively large number of bolster springs of uniform length which is effectually reinforced against distortion under heavy 120 loads imposed thereon through the supporting springs.

125 It should also be noted that the bolster guiding means permits suspension of the brake beams from supporting lugs indicated at 21 located closely adjacent the bolster receiving opening and that the narrow bolster provides space for the brake beams closely adjacent the center of the truck so that the 130 number of bolster supporting springs may

be increased without an increase in the length of the wheel base.

Furthermore, it is to be understood that the particular form of apparatus shown and described, and the particular procedure set forth, are presented for purposes of explanation and illustration and that various modifications of said apparatus and procedure can be made without departing from our invention as defined in the appended claims.

What we claim is:

1. In a railway car truck, a bolster, side frames each having an upper compression chord, a lower tension chord and spaced columns connecting said chords and forming between them an opening to receive an end of said bolster, said columns having laterally extending webs forming the inner faces thereof, each tension chord having a flat horizontal portion extending from the base of one column to the base of the other and reinforcing webs on opposite sides of the horizontal portion extending downwardly at an incline from the columns to the horizontal portion inwardly of the columns, said webs being integral with the columns and merging into the inner faces thereof and a group of bolster supporting springs on said horizontal portion, certain springs of said group occupying the spaces adjacent the columns between said reinforcing webs.

2. In a railway car truck, a bolster, side frames each having an upper compression chord, a lower tension chord and spaced columns connecting said chords and forming between them an opening to receive an end of said bolster, said columns having laterally extending webs forming the inner faces thereof, each tension chord having a flat horizontal portion extending from the base of one column to the base of the other and reinforcing webs on opposite sides thereof extending downwardly at an incline from the columns to the horizontal portion inwardly of the columns, said webs being integral with the columns and merging into the inner faces thereof and a group of bolster supporting springs on said horizontal portion, said group of springs comprising a central row of springs between said columns, the endmost springs of which occupy the spaces between said reinforcing webs, other springs of said group being positioned on opposite sides of the central row.

3. In a railway car truck, a bolster, side frames, each having an upper compression chord, a lower tension chord and spaced columns connecting said chords and forming between them an opening to receive an end of said bolster, said columns having laterally extending webs forming the inner faces thereof, each tension chord having a horizontal portion extending from the base of one column to the base of the other and reinforcing

webs on opposite sides thereof extending downwardly at an incline from the columns to the horizontal portion inwardly of the columns, said webs being integral with the columns and merging into the inner faces thereof, a spring plank having widened end portions extending into the spaces between the inner and outer reinforcing webs, and a group of bolster supporting springs seated on said plank at each end thereof.

4. In a railway car truck, a bolster, side frames, each having an upper compression chord, a lower tension chord and spaced columns connecting said chords and forming between them an opening to receive an end of said bolster, said columns having laterally extending webs forming the inner faces thereof, each tension chord having a horizontal portion extending from the base of one column to the base of the other and reinforcing webs on opposite sides thereof extending downwardly at an incline from the columns to the horizontal portion inwardly of the columns, said webs being integral with the columns and merging into the inner faces thereof, a spring plank having widened end portions extending into the spaces between the inner and outer reinforcing webs, and a group of bolster supporting springs seated on said plank at each end thereof, certain of said springs being seated on the portions of the plank projecting into the spaces between the reinforcing webs.

5. In a railway car truck, a side frame having an upper compression chord, a tension chord having a central horizontal spring supporting portion and inclined end portions joining said central portion with the ends of the compression chord, and upright columns extending from the ends of the horizontal portion to the compression chord and forming between them the bolster receiving opening, said columns having laterally extending webs forming the inner faces thereof, said horizontal portion having a flat top surface extending from the base of one column to the base of the other, and said tension chord having laterally projecting side flanges extending along the top of the horizontal portion and upwardly at an incline from point spaced inwardly from the columns and merging into the inner faces of the columns to form reinforcing webs.

6. In a railway car truck, a side frame having an upper compression chord, a tension chord having a central horizontal portion and inclined end portions joining said central portion with the ends of the compression chord, and upright columns extending from the ends of the horizontal portion to the compression chord and forming between them the bolster receiving opening, said columns having laterally extending webs forming the inner faces thereof, said horizontal portion having lateral flanges along the opposite sides at the

top thereof which are inclined upwardly from points spaced inwardly from the columns and merge into the inner faces of the columns to strengthen the tension chord at the juncture 5 of the horizontal portion with the inclined end, the top face of the horizontal portion being flat and extending to the base of the columns between the inclined portions of the flanges to provide spring receiving recesses 10 adjacent the columns.

7. In a railway car truck, a side frame having an upper compression chord, a tension chord having a central horizontal portion and inclined end portions joining said central 15 portion with the ends of the compression chord, upright columns extending from the ends of the horizontal portion to the compression chord and forming between them the bolster receiving opening, said columns 20 having inner faces extending to the horizontal spring supporting portion and inwardly offset upper portions comprising bolster guides, said horizontal portion having lateral flanges which are inclined upwardly 25 from points spaced inwardly from the columns and merge into the inner faces of the columns to strengthen the tension chord at the juncture of the horizontal portion with the inclined end portions, the top face of the 30 horizontal portion extending to the bases of the columns between the inclined portions of the flanges to provide spring receiving recesses adjacent the columns.

8. In a railway car truck, a side frame having an upper compression chord, a tension chord having a central horizontal spring supporting portion and inclined end portions joining said central portion with the ends of the compression chord, and upright columns 35 extending from the ends of the horizontal portion to the compression chord and forming between them the bolster receiving opening, said columns having laterally extending webs forming the inner faces thereof, said 40 horizontal portion having a flat top surface extending from the base of one column to the base of the other, and said tension chord having side flanges extending along the top of the horizontal portion and upwardly at an incline from points spaced inwardly from the 45 columns, said inclined portions of the flanges being curved inwardly and forming reinforcing webs merging into the faces of the columns, whereby the horizontal spring 50 supporting portion is of greatest length 55 along the center line thereof.

9. In a railway car truck, a side frame having an upper compression chord, a tension chord having a central horizontal portion 60 and inclined end portions joining said central portion with the ends of the compression chord, and upright columns extending from the ends of the horizontal portion to the compression chord and forming between them the bolster receiving opening, said hori- 65

70 zontal portion having lateral flanges along opposite sides at the top thereof which form lateral extensions of the top surface of the horizontal portion and are inclined upwardly from points spaced inwardly from the columns to strengthen the tension chord at the juncture of the horizontal portion with the inclined end, said columns having webs forming their inner faces which are joined to said horizontal portion, the top face of the 75 horizontal portion being flat and extending to the base of the columns between the inclined portions of the flanges to provide spring receiving recesses adjacent the 80 columns, the inner faces of said columns being spaced the full length of the horizontal portion along the longitudinal center line thereof.

10. In a railway car truck, a side frame in the form of a casting comprising an upper compression chord and a lower tension chord having a horizontal central portion and inclined end portions connecting the said central portion to the end portions of the compression chord, and upright columns connecting the ends of the horizontal portion to the compression chord and having webs forming the inner faces thereof, the body of the horizontal portion having a flat top from the web of one column to the web of the other and having laterally projecting side flanges with horizontal central portions forming extensions of said flat top and inclined end portions extending upwardly from points spaced inwardly from the 95 columns, and reinforcing ribs interposed between the under sides of the flanges and the side faces of the body of the horizontal portion.

In testimony whereof, we affix our signatures.
